SPEED REGULATING MECHANISM

Win W. Paget, Michigan City, Ind., assignor to
 Joy Manufacturing Company, a corporation of
 Pennsylvania

Application December 15, 1944, Serial No. 568,384

27 Claims. (Cl. 230—5)

1

My invention relates to speed regulating mechanisms for motor driven compressors, and more particularly to mechanisms for regulating the supply of operating fluid to driving engines for compressors.

Engine driven compressor systems are ordinarily provided with some form of mechanism for regulating the supply of operating fluid to the engine in response to the pressures in a receiver to which fluid is supplied from the compressor. It is desirable that the mechanism operate to cause a gradual reduction in the engine speed as the receiver pressure increases through a predetermined range. When the pressure reaches the upper limit of the range, the compressor is unloaded and the driving engine is slowed down to an idling speed. On reduction of the receiver pressure to a predetermined lower value, the driving engine is speeded up and the compressor is reloaded.

In a preferred embodiment my invention contemplates the provision of a mechanism which responds to pressures in a receiver for regulating the supply of operating fluid to an engine so as to vary the speed of the latter in the manner described above, and operating to control the flow of fluid relative to an unloading device when the desired pressure is reached. A speed responsive governor is provided for urging a control element in a direction to reduce the supply of operating fluid to the engine, and yieldable means resist the action of the speed responsive governor by amounts varying with the receiver pressure. A pressure responsive device is subjected continuously to the receiver pressures and operates as the pressure increases to reduce the resistance offered by the yielding means to the action of the governor. On predetermined movement of the pressure responsive device, valve means are operated to supply pressure fluid to unloading means for the compressor and to another pressure responsive device which moves the control element to a position effecting operation of the engine at an idling speed. In one form of the invention, when the same is utilized in a system including a separate slow-down device, the valve means may operate to supply pressure fluid to a pressure responsive device for preventing reloading occurring due to there being a reduction in the forces exerted by the flyballs, as a result of the slowing down of the engine by the slow-down device, to such a degree that the control element would not be prevented by the forces usually then acting on it from moving to a reloading position.

2

An object of my invention is to provide improved means for regulating the supply of operating fluid to an engine driving a compressor. Another object is to provide improved means for varying the supply of operating fluid to the driving engine for a compressor in response to the pressures in the compressor discharge line. Still another object is to provide an improved mechanism for reducing gradually the speed of a driving engine for a compressor as the discharge pressure of the latter increases through a predetermined range and operating at a pressure above the upper limit of the pressure range for effecting an unloading of the compressor and a slowing down of the engine to an idling speed. Yet another object is to provide an improved regulating means which operates to oppose a variable resistance to the action of a speed governor, such resistance varying as there occur variations in the discharge pressures of a compressor. Still another object is to provide an improved regulating mechanism which operates to reduce the resistance to operation of a speed governor in a speed reducing direction as the discharge pressure of a compressor increases. Other objects will appear in the course of the following description.

In the drawings there are shown for purposes of illustration two forms which my invention may assume in practice.

30 In these drawings:

Fig. 1 is a side elevational view of an internal combustion engine having my improved regulating mechanism in its preferred form associated therewith.

35 Fig. 2 is an enlarged vertical sectional view of the improved regulating mechanism shown in Fig. 1.

Fig. 3 is a central sectional view through a cylinder head and a portion of a cylinder of a compressor adapted to be driven by the engine shown in Fig. 1.

40 Fig. 4 is an enlarged vertical sectional view taken on the plane of the line 4—4 of Fig. 1.

Fig. 5 is a fragmentary sectional view taken on the plane of the line 5—5 of Fig. 4.

45 Fig. 6 is a schematic diagram showing the regulating mechanism connected in a control system for the compressor and its driving engine.

Fig. 7 is a view like that of Fig. 1 showing another form of my improved regulating mechanism connected to an internal combustion engine.

50 Fig. 8 is an enlarged vertical sectional view of the regulating mechanism shown in Fig. 7.

Fig. 9 is an enlarged fragmentary sectional view taken on the plane of the line 9—9 of Fig. 7.

Fig. 10 is a fragmentary sectional view taken on the plane of the line 10—10 of Fig. 9.

Fig. 11 is a schematic diagram showing the regulating mechanism of Fig. 8 connected in a compressor control system.

In Figs. 1 to 6 my improved regulating mechanism is shown in its preferred form associated with an internal combustion engine for controlling the supply of operating fluid to the latter in desired relation to variations in pressure in a receiver of a compressor system. The internal combustion engine, generally designated 1, has a carburetor 2 containing a throttle valve 3, Figs. 1 and 6, which is regulated by my improved regulating mechanism, generally designated 4. The power shaft of the engine is operatively connected by means, not shown, to a compressor having pistons one of which is shown at 6 and effects reciprocation of the latter in a bore 8 of a compressor cylinder 9. It will be understood that other compressor cylinders containing pistons connected for reciprocation by the power shaft may be provided if desired and will ordinarily be used. Fluid is admitted through an intake passage 11 and past an inlet valve 12 to the cylinder bore 8 where it is compressed, and thereafter discharged past a discharge valve 14 to a passage 15 which is connected by suitable connections, not shown, to a receiver 16 shown in Fig. 6. The cylinder has a head 18 connected thereto, as by bolts 19, and attached to the head, as by bolts 20, is a member 22 having a chamber 23 which receives a piston 25 carrying a plate portion 26. Rods 27 are connected to the plate portion 26 and extend through openings in the cylinder head to engage the inlet valve 12 for unseating the latter and effecting an unloading of the compressor cylinder when the piston 25 is subjected to pressure fluid. The piston 25 is normally held in its raised position by a spring 28 and is adapted to be forced to its lower position against the action of the spring 28 by pressure fluid supplied to the chamber 23 through a conduit 30.

The improved regulating mechanism 4 comprises a block 32 having a recess 33 containing a bellows device 34. Connected to the block at the open end of the recess is an annular member 36 having a sleeve portion 38 at its inner edge projecting axially into the bellows device 34. Clamped between the member 36 and the block 32 is an annular plate member 40 to which one end of the bellows device 34 is connected, as by brazing or soldering. The other end of the bellows device is connected in a similar manner to a member 42 having a sleeve portion 43 which is reciprocably received within the sleeve portion 38 of the member 36. The space within the recess 33 surrounding the bellows device 34 has pressure fluid supplied to it from the receiver past a check valve 44 which is movable to a position for permitting free admission to the recess 33 and is adapted to seat on a projecting seat 45 surrounding a recess 46 in the block 32. Pressure fluid is supplied to the recess 43 through a passage 47 which is connected in communication with the receiver by a conduit 48. The valve 44 may be ported, or may loosely surround its guide pin P, or may have its seat slotted, to permit the pressure in the recess 33 to lower as receiver pressure falls off. By reason of the check valve 44, there will be prevented any sudden expansion of the bellows device 34 should the pressure in the system drop suddenly for some reason, such as because of a break in the fluid conducting

system. The block 32 is provided with a projecting portion 50 to which a lever 51 is pivotally connected at a point between its ends, as at 53. Pivotally connected to the lever 51 at a point 54 below the pivot point 53 and in alignment with the sleeve portion 43 of the member 42 is a pin 56 which extends through the sleeve portions 38 and 43 and engages the member 42 for holding the latter normally in engagement with the inner end of the recess 33. The block member 32 is also provided with a downwardly projecting portion 58 having an opening receiving an eyebolt 59 carrying lock nuts 60, and a spring 62 is connected at one end to the eyebolt 59 and is connected at its other end to the lower end of the lever 51.

Keyed to a shaft 63 projecting from the engine housing 64 adjacent the block 32 is a control lever 65 having a portion 66 projecting downwardly below the shaft 63, and a spring 67 is connected at one end to the lower end of the lever 51 and at its other end to an eyebolt 68 extending through an opening between the ends of the portion 66 of the control lever and held in place by a lock nut 69. Extending through another and lower opening in the projecting portion 58 of the block 32 at a point below the eyebolt 59 is another eyebolt 70 having lock nuts 71, and a spring 73 is connected between this eyebolt and the lower end of the projecting portion 66 of the lever 65. Formed integral with the control lever 65 adjacent the shaft 63 is a transversely projecting portion 75 which is adapted to be engaged by a stem 76 formed on a piston 78 slidably received within a bore 80 formed in an enlarged portion 81 at the outer end of the projecting portion 58 on the block 32. The piston 78 is normally held in its raised position by a spring 82 which acts between the piston and an annular member 85 supported by a split ring 87 fitting within an annular groove adjacent the lower end of the bore 80. When pressure fluid is supplied to the bore 80 at the upper side of the piston 78, the latter is moved downwardly against the action of the spring 82 and engages the projecting portion 75 of the lever 65 for swinging the latter in a counter-clockwise direction. Carried by the lever 65 is a bolt 90 which is engageable with the side of the enlarged portion 81 for limiting the swinging of the lever in a counter-clockwise direction. The bolt 90 is adjustable to various positions and may be locked in place by a lock nut 92. A lever 94 is pivotally supported at its lower end, as shown in Fig. 4, upon the shaft 63, and its upper end is connected to a rod 95 which is attached to an arm 96 connected to the throttle valve 3. The upper end of the lever 65 is provided with a transversely extending portion 98 having an arcuate slot 99, and a pin 100 is fixed in an opening in the lever 94 between the ends of the latter and extends through the slot 99. The levers 65 and 94 are adjustable angularly relative to each other by reason of the slot 99, and a wing nut 101 threaded on the pin 100 is adapted to clamp the levers in the desired adjusted positions.

Formed in the block 32 above the recess 33 are stepped bores 103 and 104 providing at their juncture a valve seat 105 which is engageable by a cup-shaped valve member 106 slidably received within the larger bore 103. The valve member 106 has grooves 107 extending longitudinally thereof in its outer surface for connecting the bores 103 and 104 in communication with each other when the valve member is unseated. A

spring 103 acts between a plug 109 closing the outer end of the bore 103 and the valve member 106 for urging the latter toward the seat 105. Threaded into an opening in the block 32 at the outer end of the bore 104 is a member 110 providing a valve seat 111, and a valve member 112 has a head portion 113 engageable with the seat 111 and a winged stem 114 extending through an opening in the member 110 and engageable with the valve member 106 for unseating the latter when the head portion 113 is caused to engage the seat. The valve member 112 is normally held in a position with its head portion 113 unseated, by the action of the spring 108 on the valve member 106. Threaded into an opening in the upper end of the lever 51 is a pin 115 which is engageable with the head portion 113 of the valve member 112 for moving the latter to unseat the valve member 106 and to cause the head portion 113 to engage its seat when the lever is swung in a counter-clockwise direction. When the head portion 113 is unseated, the bore 104 is connected through the spaces between the wings on the stem 114 and past the seat 111 to atmosphere. The bore 103 is connected directly in communication with the receiver 16 by a conduit 116, and the bore 104 is connected by a conduit 117 through a valve mechanism 118 to a conduit 119 which communicates with the conduits 30 leading to the compressor unloading pistons 25. As shown in Fig. 6, two conduits 30 are provided, the compressor in this case having two cylinders, each having an unloading mechanism. In many units, four or more cylinders may be used. The valve mechanism 118 is of a standard type and permits a free flow of fluid toward the unloading mechanisms and restricts the flow in the opposite direction. The bore 104 is also connected by a passage 121 to the bore 80 at the upper side of the piston 78.

The shaft 63, as shown in Fig. 4, is rotatably supported by a bushing 124 extending through an opening in the engine housing, and fixed to the inner end of the shaft is a crank 125 carrying a crankpin 126. Extending longitudinally through the engine housing is a shaft 127 which is slidably supported at one end in an opening formed in a wall 128 of the housing and is similarly supported at its other end in an opening 129 extending longitudinally through an elongated member 130 rotatably supported by bearings 131 carried by the housing. Suitably connected to one end of the member 130 is a gear 132, which meshes with a gear 133 driven in any suitable manner from the power shaft of the engine 1. The member 130 is provided with a slot 134 into which the shaft 127 projects, and flyweights 135 are pivotally connected to the member 130 and have inwardly projecting portions 136 which are adapted to engage the end of the shaft 127 for forcing the latter longitudinally to the left, in Fig. 5, as the weights swing outwardly. Fixed to the shaft 127 is a spool-shaped member 138 having an annular groove 139 into which the crankpin 126 projects. It will be seen that the movement of the rod 127 by the outward swinging of the weights 135 causes the spool-shaped member 138 to move the crankpin 126 and so rotate the shaft 63 in a direction to swing the control lever 65 in a counter-clockwise direction, as shown in Fig. 2, against the action of springs 67 and 73.

The operation of the regulating mechanism is as follows: When the pressure in the receiver increases to a value sufficient to start to compress

the bellows device 34 and swing the lever 51 against the action of the spring 62, there will be, on swinging of the lever 51, a reduction in the force offered by the spring 67 for holding the control lever 65 against rotation in a counter-clockwise direction. The resistance offered by the spring 62 to the swinging of the lever 51 may be regulated by adjusting the eyebolt 59, this adjustment being made so that the bellows device 34 operates to initiate a slowing down of the engine at the desired discharge pressure. A reduction of the force holding the lever 65 against swinging in a counter-clockwise direction results in an outward swinging of the weights 135 and a movement of the shaft 127 in a direction to effect rotation of the shaft 63 in a counter-clockwise direction. The control lever 65 is swung with the shaft 63 and causes the lever 94 to swing with it and move the rod 95 in a direction to partially close the throttle valve 3 of the engine. As the receiver pressure continues to increase, the control lever 65 continues to swing in a direction to reduce the supply of operating fluid to the engine. After the lever 51 has been swung a predetermined distance by the bellows device 34, the pin 115 carried by the upper end of the lever engages the head portion 113 of the valve member 112 and presses the latter against the valve member 106, which has been held seated by receiver pressure acting in the bore 103 against its left-hand end and by the spring 108. When the receiver pressure has increased by an amount, depending on the relative areas of the valve member 106 and the bellows 34 and the strength of the spring 108, sufficient to unseat the valve member 106, the lever 51 will be swung further in a counter-clockwise direction by the bellows 34 unseating the valve member 106 and seating the valve member 112 to cut off communication between the bore 104 and the atmosphere. Pressure fluid then flows from the receiver 16 through the conduit 116 to the bore 103 where it passes through the grooves 107 to the bore 104. The pressure fluid passes from the bore 104 through the passage 121 to the bore 80 where it acts on the piston 78 and forces the latter downwardly to engage the projecting portion 75 of the control lever 65 and effect a swinging of the latter in a counter-clockwise direction until the throttle valve for the engine has restricted the flow of fluid to such an extent that the engine operates at an idling speed. The pressure fluid also passes from the bore 104 through the conduit 117, the valve mechanism 118 and the conduit 119 to the conduits 30 leading to the unloading mechanisms for the compressor cylinders. The swinging of the control lever 65 by the piston 78 causes a substantial increase in the tension of the spring 67 and makes it necessary that the pressure in the receiver drop somewhat before the lever 51 will be able to swing in a clockwise direction about its pivot pin 53. It will further be noted that the supply of receiver pressure to the bore 104 resulted in an equalizing of the pressures at opposite ends of the valve member 106 and a reduction in the force which resisted the motion of the lever 51 in a counter-clockwise direction so that the seating of valve 112 readily took place. When this valve is seated receiver pressure acts against an area on the valve member 112 equal to the area inside its seat, and exerts a force upon this valve tending to push the pin 115 to the right in Fig. 2. This means that a reduction in receiver pressure in addition

to that needed to compensate for the increased tension of spring 67 will be required before the lever 51 will swing again in a clockwise direction, because to unseat the valve 106 took more force than is required to keep valve 112 seated. When the receiver pressure drops the requisite amount and the lever 51 swings in a clockwise direction under the action of spring 62, the head 113 of the valve member 112 will be disengaged and the latter will be unseated by the action of the spring 106 on the valve member 106. The unseating of the valve member 112 causes the bore 104 to be vented to atmosphere so that pressure fluid escapes immediately from the space above the piston 78 through the passage 121 to atmosphere. The piston 78 is moved upwardly by the spring 62 out of engagement with the projecting portion 75 of the control lever and the latter is caused to swing by the springs 67 and 73 in a direction to increase the supply of operating fluid to the engine. The engine speeds up, causing the weights 135 of the governor to swing outwardly against the action of springs 67 and 73 until the forces on the control lever are balanced, the position assumed by the control lever being determined by the pressure acting on the bellows device 34. The escape of pressure fluid from the unloading mechanisms of the compressor will be restricted by the valve mechanism 118 so that a reloading of the compressor will not take place until the speed of the engine has been increased.

In Figs. 7 to 11 there is shown an internal combustion engine 145 having the supply of operating fluid delivered thereto controlled by another form of regulating mechanism, generally designated 146. This regulating mechanism includes a block 148 having a recess 149 containing a bellows device 150. Connected to the block at the open end of the recess is a member 152 having a sleeve portion 153 extending axially within the bellows device 150. Clamped between the member 152 and the block is an annular plate 155 to which one end of the bellows device 150 is connected, as by brazing, and the other end of the bellows device is connected in a similar manner to a member 156 having a sleeve portion 157 slidably received within the sleeve portion 153. Pivotaly connected at a stationary point 160 is a lever 161 having a pin 162 pivotally connected thereto at a point in axial alinement with the sleeve portion 153, and this pin extends through the sleeve portion 153 into engagement with the member 156. The block 148 is provided with an upwardly projecting portion 164 carrying an eyebolt 165 to which one end of a spring 167 is connected, and the opposite end of the spring 167 is connected to the upper end of the lever 161 for resisting swinging of the latter by the bellows device 150. The space in the recess 149 surrounding the bellows device 150 is connected directly in communication with the receiver through a conduit 169 which might if desired be supplied with any suitable check valve arrangement similar to the valve device 44, 45, P. The pressure fluid acting on the exterior of the bellows device 150 tends to compress the latter and swing the lever 161 in a clockwise direction against the action of the spring 167.

Keyed to a shaft 172 projecting from the engine housing is a control lever 174 which is connected by a spring 175 to the upper end of the lever 161. The control lever 174 is connected at its upper end to a rod 177 which is attached to an arm 178 fixed to a throttle valve 179 for the engine.

Movement of the control lever 174 in a clockwise direction causes the throttle valve 179 to be actuated in a manner to restrict the flow of operating fluid to the engine. The control lever 174 is provided with an adjustable member 180 which is engageable with an abutment surface 182 on the engine housing for limiting swinging of the control lever in a clockwise direction. Supported by the upwardly projecting portion 164 of the block 148 is another eyebolt 184 to which one end of a spring 185 is connected, and the opposite end of the spring 185 is connected to the control lever 174.

Formed in the block 148 beneath the recess 149 is a recess 187 containing a member 188 having stepped bores 189 and 190. Slidably received within the larger bore 189 is a valve member 191 which is engageable with the seat-providing shoulder formed at the juncture of the bores 189 and 190 for cutting off communication therebetween. A spring 192 acts between a plug 193 closing the outer end of the recess 187 and the valve member 191 for urging the latter into an engagement with the seat-providing shoulder between the bores. The member 188 is also provided with a bore 195 which slidably receives a plunger 196 having a valve portion 197 for controlling the flow of fluid from the bore 190 through a port 198 to passages 199 communicating with the atmosphere. Projecting from the valve portion 197 is a stem 201 which extends through the port 198 and is engageable with the valve member 191 for moving the latter toward its open position when the valve portion 197 is moved toward its seat. Formed in the walls of the bore 189 adjacent the juncture of the bores 189 and 190 is an annular groove 203, and ports 204 formed in the valve member 191 connect the space in the bore 189 at the left of the valve member 191 in communication with the annular groove 203. The space in the bore 189 at the left of the valve member 191 has pressure fluid supplied thereto from the receiver 18 through a conduit 205. When the valve member 191 is unseated fluid flows from the groove 203 to the bore 190 where it enters a passage 206 and is conducted to a conduit 207 which is connected, as shown in Fig. 11, to conduits 208 and 209. Conduit 208 communicates with a cylinder member 211 which contains a suitable fluid actuated means, not shown, such as a piston, which is connected to an arm 212 of a throttle valve 213. On supply of pressure fluid to the cylinder member 211, the arm 212 is actuated to move the throttle valve 213 in a closing direction. The throttle valve 213 is moved by the device 211, 212 to slow the engine down to a desired minimum idling speed. The conduit 209 is connected through a valve mechanism 215 to a conduit 216 which communicates with conduits 30 leading to the unloading mechanisms for the compressor cylinders. The valve mechanism 215 operates in the same manner as the valve mechanism 118 shown in the first form of the invention, that is, to permit a free flow of fluid to the unloading mechanism and to restrict the flow in the opposite direction. The lever 161 is provided with a downwardly projecting portion 218 carrying an adjustable member 219 which is engageable with the plunger 196 for forcing the latter in a direction to cut off communication between the bore 190 and the atmosphere and to move the valve member 191 to its open position so as to supply pressure fluid to the bore 190.

When the valve 191 is unseated, the pressures 75 tend to equalize at its opposite ends and thus the

force that opposed movement of pin 219 to unseat the valve is reduced, and replaced by a smaller force equal to that exerted by receiver pressure on an area equal to the cross-sectional area of the port 192 and that due to spring 192, so that valve 191 opens smartly, and there will be needed a drop in receiver pressure below that required to unseat valve 191 to prevent its closing again.

The shaft 172 extends, as shown in Fig. 9, 10 through a bushing 224 fixed in an opening in the wall of the engine housing, and the inner end of the shaft 172 carries a crank 225 having a pin 226 which extends into an annular groove 227 in a spool-shaped member 228 slidably mounted on a shaft 229 extending longitudinally through the housing of the engine. Suitably connected to one end of the shaft 229 is a gear 230 meshing with a gear 231 which is driven in any suitable manner from the power shaft of the engine. Extending longitudinally through the shaft 229 is a bore 232 in which a rod 234 is slidably contained; and this rod is connected at one end to the spool-shaped member 228 by a pin 235 which extends through an elongated slot 236 in the shaft 229. The other end of the rod 234 projects into a slot 239 formed in the shaft 229 and is engageable by inwardly projecting portions 240 formed on flyweights 241 pivotally connected to the shaft 229. As the flyweights swing outwardly about their pivotal connections to the shaft, the rod 234 is forced to the right in Fig. 9 through the bore 232 and causes the spool-shaped member 228 to slide along the shaft 229. This movement of the spool-shaped member 228 actuates the pin 226 to rotate the shaft 172 in a direction to effect a swinging of the control lever 174 in a clockwise direction, as shown in Fig. 8.

The control lever 174 is provided with a portion 245 projecting downwardly below the shaft 172, and this portion of the shaft is engageable by a piston 246 which is slidably mounted in a bore 247 of a cylinder 248. Pressure fluid is supplied to the bore 247 at its inner end through a conduit 250 which is connected in communication with the conduit 208. When pressure fluid is supplied to the bore 247, the piston 246 is forced outwardly against the portion 245 of the control lever for holding the latter in a position with its adjustable member 180 engaging the abutment 50 surface 182.

The operation of this regulating mechanism is similar to that of the first form of the invention. When the receiver pressure increases to a value sufficient to start to compress the bellows device 150 and swing the lever 161 in a clockwise direction against the action of the spring 167, the resistance offered by the spring 175 to a swinging of the control lever 174 in a clockwise direction will be reduced. The flyweights 241 of the speed governor will then operate to move the rod 234 and effect a rotation of the shaft 172 in a clockwise direction, as shown in Fig. 8. The control lever 174 will swing with the shaft 172 against the action of the springs 175 and 185 and will operate the rod 177 to move the throttle valve 179 toward its closed position for restricting the flow of operating fluid to the engine. When the lever 161 is swung by the bellows device 150 to a point where the plunger 196 is moved by the adjustable member 219 to a position seating the valve portion 197 and unseating the valve 191, the venting of the bore 190 will be cut off and pressure fluid will be supplied from the receiver past the valve member 191 to the bore 190. The

pressure fluid will then flow from the bore 190 through the passage 206 to the conduit 207 where it will be conducted to the conduits 208, 209 and 250. Pressure fluid entering the conduit 208 will be conducted to the cylinder member 211 where it acts to effect a closing of the throttle valve 213 until the engine operates at an idling speed. The conduit 209 will conduct the pressure fluid through the valve mechanism 215 to the conduit 216 where it is conducted to the conduits 30 leading to the unloading mechanisms for the compressor cylinders and effects an unloading of the latter. The operation of the engine at an idling speed causes the speed governor to reduce its force tending to hold the control lever 174 in a position for restricting the flow of operating fluid to the engine past the throttle valve 179, and, if nothing were provided for holding the control lever in its valve-restricting position, the springs 175 and 185 would operate to swing the control lever in a counter-clockwise direction because the speed responsive governor exerted force would be reduced. This would not increase the engine speed, because valve 213 limits that. Movement of the control lever in this counter-clockwise direction would result, however, in a reduction in the force tending to hold the lever 161 against movement in a counter-clockwise direction, and the lever 161 would then swing in this direction 30 and release the plunger 196, cutting off the flow of pressure fluid to the unloading means and to the throttle closing means. Such movement of the control lever is prevented, however, by reason of the fact that pressure fluid is delivered through the conduit 250 to the cylinder bore 247 where it acts on the piston 246 and forces the latter against the projecting portion 245 of the control lever for holding the latter against movement in a counter-clockwise direction. If the control lever 174 were swung by the speed governor, by the time the plunger 246 becomes operative, to a position in which its adjustable member 180 engages the abutment surface 182, there would be no further swinging of the control lever 174 by the piston 246 on supply of pressure fluid to the latter, and the tension of the spring 175 would remain the same as it was at the moment the lever 161 forced the plunger 196 to its innermost position. Under this condition, the pressure acting on the bellows device 150 would need to drop only a comparatively small amount before the lever 161 would be swung in a counter-clockwise direction to disengage the plunger 196 and vent fluid from the conduits 208, 209 and 250, causing the engine to be speeded up to a point where it would again come under the control of the speed governor and the bellows device 150 and cause the compressor to be reloaded. Some reduction—a definite one—would even then be required, because of the change in forces involved on the opening of valve 191. If the member 180 on the control lever 174 and the member 219 on the control lever 161 are so adjusted that the plunger 196 is forced inwardly by the lever 161 and unseats the valve 191 before the member 180 engages its abutment surface, the supply of pressure fluid to the cylinder member 248 will cause the piston 246 to act against the portion 245 of the lever 174 and swing the latter until its member 180 engages the abutment surface 182 and will hold the lever 174 against counter-clockwise movement and, as above noted, prevent the lessened force exerted by the flyballs at the slower speed caused by the closing movement of the valve 213 from permit-

ting the lever 174 from moving back and reducing the tension of spring 175 enough to permit repositioning of valves 191 and 197 to cause re-loading without a reduction in receiver pressure taking place. Desirably the parts will be so adjusted that the movement of the lever 174 to bring the stop element against the stop surface 182 will involve a small increase in the tension of the spring 175 since the lever 161 will be held by its engagement with the plunger 196 against swinging in a clockwise direction. With this arrangement, the pressure acting on the bellows device 150 will need to drop to a somewhat lower value before the lever 161 will be swung in a counter-clockwise direction to permit the plunger 196 to move outwardly and vent the conduits 208, 209 and 250 and effect a speeding up of the engine and a reloading of the compressor.

As a result of my invention there is provided an improved regulating mechanism which operates to reduce gradually the supply of operating fluid to the driving engine for a compressor as the discharge pressures of the latter increase through a predetermined range, and which operates at a pre-determined maximum discharge pressure for supplying pressure fluid to effect a slowing down of the engine to an idling speed and an unloading of the compressor. It will be noted that the regulating mechanism is provided with various adjustable means whereby it will operate to reduce the speed of the driving engine gradually through any desired pressure range and will effect a slowing down of the engine to an idling speed and an unloading of the compressor when any desired maximum pressure is reached. A speeding up of the engine and a reloading of the compressor may also be obtained within reasonable limits on a drop in pressure to any desired value.

By the term "operating fluid" it will be understood that I intend to describe, but without limitation thereto other than may be required by the prior art, the combustible mixture exploded in gasoline engine cylinders, and vaporized or other liquid fuels utilized in Diesel engines; and my invention is not to be understood as limited to use with any particular operating fluid.

While there are in this application specifically described two forms which the invention may assume in practice, it will be understood that these forms of the same are shown for purposes of illustration, and that the invention may be modified and embodied in various other forms without departing from its spirit or the scope of the appended claims.

What I claim as new and desire to secure by Letters Patent is:

1. A speed regulating mechanism for an engine driven compressor comprising, in combination, means for controlling the supply of operating fluid to the engine, a speed governor for urging said controlling means in a direction to reduce the supply of operating fluid, means for yieldably resisting the action of said speed governor, means responsive to compressor discharge pressure for varying the resistance offered by said yieldable means progressively to reduce such resistance as compressor discharge pressure increases between predetermined limits, means for subjecting said pressure responsive means continuously to compressor discharge pressure, other pressure responsive means for actuating said controlling means in a direction to reduce the supply of operating fluid, and means for

supplying compressor discharge pressure to said last mentioned pressure responsive means automatically only when the discharge pressure reaches a predetermined maximum value.

5 2. A speed regulating mechanism for an engine driven compressor comprising, in combination, means for controlling the supply of operating fluid to the engine, a speed governor for urging said controlling means in a direction to reduce the supply of operating fluid, means for yieldably resisting the action of said speed governor, means responsive to compressor discharge pressure for varying the resistance offered by said yieldable means progressively to reduce such resistance as compressor discharge pressure increases between predetermined limits, means for subjecting said pressure responsive means continuously to compressor discharge pressure, pressure responsive means for actuating said controlling means in a direction to reduce the supply of operating fluid, means including a valve member for controlling the supply of pressure fluid to said last mentioned pressure responsive means, and means controlled by said first mentioned pressure responsive means for controlling said valve member.

20 3. A speed regulating mechanism for an engine driven compressor comprising, in combination, means for controlling the supply of operating fluid to the engine, a speed governor for urging said controlling means in a direction to reduce the supply of operating fluid, means for yieldably resisting the action of said speed governor, means responsive to compressor discharge pressure for varying the resistance offered by said yieldable means progressively to reduce such resistance as compressor discharge pressure increases between predetermined limits, means for subjecting said pressure responsive means continuously to compressor discharge pressure, pressure responsive means for actuating said controlling means in a direction to reduce the supply of operating fluid, means including a valve member movable to an open position for supplying pressure fluid to said last mentioned pressure responsive means, and means controlled by said first mentioned pressure responsive means for controlling said valve member, operative to move said valve member to its open position when said first mentioned pressure responsive means is subjected to a predetermined maximum discharge pressure.

25 4. A regulating mechanism for an engine driven compressor having fluid actuated unloading means comprising, in combination, means for controlling the supply of operating fluid to the engine, a speed governor for urging said controlling means in a direction to reduce the supply of operating fluid, means for yieldably resisting the action of said speed governor, means responsive to compressor discharge pressure for varying the resistance offered by said yieldable means progressively to reduce such resistance as compressor discharge pressure increases between predetermined limits, other pressure responsive means for actuating said controlling means to reduce the supply of operating fluid, and means for supplying compressor discharge pressure to said last mentioned pressure responsive means and to the compressor unloading means when the discharge pressure reaches a predetermined maximum value.

30 5. A regulating mechanism for an engine driven compressor having fluid actuated unloading means comprising, in combination, means

for controlling the supply of operating fluid to the engine, a speed governor for urging said controlling means in a direction to reduce the supply of operating fluid, means for yieldably resisting the action of said speed governor, means responsive to compressor discharge pressure for varying the resistance offered by said yieldable means progressively to reduce such resistance as compressor discharge pressure increases between predetermined limits, pressure responsive means for actuating said controlling means to reduce the supply of operating fluid, means for conducting pressure fluid to said last mentioned pressure responsive means and to the compressor unloading means, means including a valve member for controlling the supply of pressure fluid to said conducting means, and means actuated by said first mentioned pressure responsive means for controlling said valve member.

6. A regulating mechanism for an engine driven compressor having fluid actuated unloading means comprising, in combination, means for controlling the supply of operating fluid to the engine, a speed governor for urging said controlling means in a direction to reduce the supply of operating fluid, means for yieldably resisting the action of said speed governor, means responsive to compressor discharge pressure for varying the resistance offered by said yieldable means progressively to reduce such resistance as compressor discharge pressure increases between predetermined limits, pressure responsive means for actuating said controlling means to reduce the supply of operating fluid, means for conducting pressure fluid to said last mentioned pressure responsive means and to the compressor unloading means, means including a valve member movable to an open position for supplying pressure fluid to said fluid conducting means, and means actuated by said first mentioned pressure responsive means for controlling said valve member, to move said valve member to its open position when said first mentioned pressure responsive means is subjected to a predetermined maximum discharge pressure.

7. A regulating mechanism for an engine driven compressor having fluid actuated unloading means comprising, in combination, means for controlling the supply of operating fluid to the engine, a speed governor for urging said controlling means in a direction to reduce the supply of operating fluid, means for yieldably resisting the action of said speed governor, means responsive to compressor discharge pressure for varying the resistance offered by said yieldable means progressively to reduce such resistance as compressor discharge pressure increases between predetermined limits, pressure responsive means for actuating said controlling means to reduce the supply of operating fluid, means for conducting pressure fluid relative to said last mentioned pressure responsive means and the compressor unloading means, valve means for controlling the connection of said fluid conducting means to fluid supply and to exhaust, and means actuated by said first mentioned pressure responsive means for controlling said valve means.

8. A regulating mechanism for an engine driven compressor having fluid actuated unloading means comprising, in combination, means for controlling the supply of operating fluid to the engine, a speed governor for urging said controlling means in a direction to reduce the supply of operating fluid, means for yieldably resisting

the action of said speed governor, means responsive to compressor discharge pressure for varying the resistance offered by said yieldable means, pressure responsive means for actuating said controlling means to reduce the supply of operating fluid, means for conducting pressure fluid relative to said last mentioned pressure responsive means and the compressor unloading means, valve means for controlling the connection of said fluid conducting means to fluid supply and to exhaust, and means actuated by said first mentioned pressure responsive means for controlling said valve means for connecting said fluid conducting means to fluid supply when said first mentioned pressure responsive means is subjected to a predetermined maximum discharge pressure.

9. A regulating mechanism for an engine driven compressor having fluid actuated unloading means comprising, in combination, a throttle valve for controlling the supply of operating fluid to the engine, means including a speed governor for urging said throttle valve toward its closed position, means for yieldably resisting the action of said speed governor, means responsive to compressor discharge pressure for varying the resistance offered by said yieldable means, said last mentioned means operative to reduce the resistance offered by said yieldable means as the discharge pressure increases, pressure responsive means for actuating said throttle valve to reduce the supply of operating fluid, and means for supplying pressure fluid to said last mentioned pressure responsive means and to the compressor unloading means when the discharge pressure reaches a predetermined maximum.

10. A regulating mechanism for an engine driven compressor having fluid actuated unloading means comprising, in combination, a throttle valve for controlling the supply of operating fluid to the engine, means including a speed governor for urging said throttle valve toward its closed position, means for yieldably resisting the action of said speed governor, means responsive to compressor discharge pressure for varying the resistance offered by said yieldable means, said last mentioned means operative to reduce the resistance offered by said yieldable means as the discharge pressure increases, pressure responsive means for actuating said throttle valve to reduce the supply of operating fluid, means for conducting pressure fluid relative to said last mentioned pressure responsive means and the compressor unloading means, valve means for controlling the connection of said fluid conducting means to fluid supply and to exhaust, and means actuated by said first mentioned pressure responsive means for controlling said valve means, said last mentioned means operative at a predetermined maximum discharge pressure for connecting said fluid conducting means to fluid supply and operative at a predetermined lower pressure for connecting said fluid conducting means to exhaust.

11. A regulating mechanism for an engine driven compressor unit which has fuel regulating means for the engine comprising a pair of throttle valves, one in the intake and one in the carburetor for the engine, said regulating means comprising fluid pressure actuated means for controlling said second mentioned throttle valve, and a speed responsive device and compressor discharge pressure responsive means co-

acting in the control of said first mentioned throttle valve, and a valve device controlled by said compressor discharge pressure responsive means for controlling fluid supply to said fluid pressure actuated controlling means for the second mentioned throttle valve.

12. A regulating mechanism for an engine driven compressor having fluid actuated unloading means comprising, in combination, a throttle valve for controlling the supply of operating fluid to the engine, means including a speed governor for urging said throttle valve toward its closed position, means for yieldably resisting the action of said speed governor, pressure responsive means for varying the resistance offered by said yieldable means, means for subjecting said last mentioned means continuously to compressor discharge pressure, pressure responsive means operative on the supply of pressure fluid thereto for holding said throttle valve against movement in an opening direction, a second throttle valve for controlling the supply of operating fluid to the engine, pressure responsive means operative on the supply of pressure fluid thereto for moving said second throttle valve to a position for effecting an operation of the engine at an idling speed, means for conducting pressure fluid relative to said second and third mentioned pressure responsive means and the unloading means, valve means for controlling the connection of said fluid conducting means to fluid supply and exhaust, and means actuated by said first mentioned pressure responsive means for controlling said valve means.

13. A regulating mechanism for an engine driven compressor having fluid actuated unloading means comprising, in combination, a throttle valve for controlling the supply of operating fluid to the engine, means including a speed governor for urging said throttle valve toward its closed position, means for yieldably resisting the action of said speed governor, pressure responsive means for varying the resistance offered by said yieldable means, means for subjecting said last mentioned means continuously to compressor discharge pressure, pressure responsive means operative on the supply of pressure fluid thereto for holding said throttle valve against movement in an opening direction, a second throttle valve for controlling the supply of operating fluid to the engine, pressure responsive means operative on the supply of pressure fluid thereto for moving said second throttle valve to a position for effecting an operation of the engine at an idling speed, means for conducting pressure fluid relative to said second and third mentioned pressure responsive means and the unloading means, valve means for controlling the connection of said fluid conducting means to fluid supply and exhaust, and means actuated by said first mentioned pressure responsive means for controlling said valve means, said last mentioned means operative at a predetermined maximum discharge pressure for actuating said valve means to connect said fluid conducting means to fluid supply.

14. A speed regulating mechanism for an engine driven compressor comprising, in combination, means for controlling the supply of operating fluid to the engine, a speed governor for urging said controlling means in a direction to reduce the supply of operating fluid, means for yieldably resisting the action of said speed governor, means responsive to compressor discharge pressure for varying the resistance offered by

5

said yieldable means, said last mentioned means operative to reduce the resistance offered by said yieldable means as the discharge pressure increases, means for subjecting said pressure responsive means continuously to compressor discharge pressure, fluid pressure operated means acting in a direction at right angles to the direction of operation of said pressure responsive means for actuating said controlling means in a direction to reduce the supply of operating fluid, and controlling means for said fluid pressure operated means controlled by said pressure responsive means.

15. A regulating mechanism for an engine driven compressor having fluid actuated unloading means, comprising, in combination, a throttle valve for controlling supply of operating fluid to the engine, means including a speed governor for urging said throttle valve toward its closed position, means for yieldably resisting the action of said speed governor, pressure responsive means for varying the resistance offered by said yieldable means, means for subjecting said last mentioned means continuously to compressor discharge pressure, a second throttle valve for controlling the supply of operating fluid to the engine, pressure responsive means operative on the supply of operating fluid thereto to move said second throttle valve to a position effecting operation of the engine at an idling speed, and means including a valve member controlled by said first mentioned pressure responsive means for supplying pressure fluid to said second mentioned pressure responsive means and said unloading means.

16. A regulating mechanism for an engine driven compressor having fluid actuated unloading means, comprising, in combination, a throttle valve for controlling supply of operating fluid to the engine, means including a speed governor for urging said throttle valve toward its closed position, a plurality of springs for yieldably resisting the action of said speed governor, pressure responsive means for varying the resistance offered by one of said springs, means for subjecting said last mentioned means continuously to compressor discharge pressure, a second throttle valve for controlling the supply of operating fluid to the engine, pressure responsive means operative on the supply of operating fluid thereto to move said second throttle valve to a position effecting operation of the engine at an idling speed, and means including a valve member controlled by said first mentioned pressure responsive means for supplying pressure fluid to said second mentioned pressure responsive means and said unloading means.

17. A regulating mechanism for an engine driven compressor having fluid actuated unloading means, comprising, in combination, a throttle valve for controlling supply of operating fluid to the engine, means including a speed governor for urging said throttle valve toward its closed position, means for yieldably resisting the action of said speed governor including a lever, a spring acting between said lever and a fixed point, a second lever and a spring acting between said second lever and said first mentioned lever, pressure responsive means for varying the resistance offered by said second mentioned spring, means for subjecting said last mentioned means continuously to compressor discharge pressure, a second throttle valve for controlling the supply of operating fluid to the engine, pressure responsive means operative on the supply of operating fluid thereto to move said second throttle valve

75

to a position effecting operation of the engine at an idling speed, and means, including a valve member controlled by said first mentioned pressure responsive means, for supplying pressure fluid to said second mentioned pressure responsive means and said unloading means.

18. A regulating mechanism for an engine driven compressor having fluid actuated unloading means, comprising, in combination, a throttle valve for controlling supply of operating fluid to the engine, means including a speed governor for urging said throttle valve toward its closed position, means for yieldably resisting the action of said speed governor including a lever, a spring acting between said lever and a fixed point, a second lever and a spring acting between said second lever and said first mentioned lever, a spring acting between said second mentioned lever and a fixed point, pressure responsive means for varying the resistance offered by said second mentioned spring, means for subjecting said last mentioned means continuously to compressor discharge pressure, a second throttle valve for controlling the supply of operating fluid to the engine, pressure responsive means operative on the supply of operating fluid thereto to move said second throttle valve to a position effecting operation of the engine at an idling speed, and means including a valve member controlled by said first mentioned pressure responsive means for supplying pressure fluid to said second mentioned pressure responsive means and said unloading means.

19. A regulating mechanism for an engine driven compressor having fluid actuated unloading means, comprising, in combination, a throttle valve for controlling supply of operating fluid to the engine, means including a speed governor for urging said throttle valve toward its closed position, means for yieldably resisting the action of said speed governor including a lever, a spring acting between said lever and a fixed point, a second lever and a spring acting between said second lever and said first mentioned lever, pressure responsive means for varying the resistance offered by said second mentioned spring, means for subjecting said last mentioned means continuously to compressor discharge pressure, a second throttle valve for controlling the supply of operating fluid to the engine, pressure responsive means operative on the supply of operating fluid thereto to move said second throttle valve to a position effecting operation of the engine at an idling speed, and means including a valve member controlled by said first mentioned pressure responsive means and positioned for unseating by said second mentioned lever for supplying pressure fluid to said second mentioned pressure responsive means and said unloading means.

20. A regulating mechanism for an engine driven compressor having fluid actuated unloading means, comprising, in combination, a throttle valve for controlling supply of operating fluid to the engine, means including a speed governor for urging said throttle valve toward its closed position, means for yieldably resisting the action of said speed governor, pressure responsive means for varying the resistance offered by said yieldable means, means for subjecting said last mentioned means continuously to compressor discharge pressure, a second throttle valve for controlling the supply of operating fluid to the engine, pressure responsive means operative on the supply of operating fluid thereto to move said second throttle valve to a position effecting oper-

ation of the engine at an idling speed, and means controlled by said first mentioned pressure responsive means for supplying pressure fluid to and venting pressure fluid from said second mentioned pressure responsive means and said unloading means, said means for supplying pressure fluid to and venting pressure fluid from said second mentioned pressure responsive means and said unloading means including a vent controlling valve and a pressure fluid supply valve movable by said vent controlling valve.

21. A regulating mechanism for an engine driven compressor having fluid actuated unloading means, comprising, in combination, a throttle valve for controlling supply of operating fluid to the engine, means including a speed governor for urging said throttle valve toward its closed position, means for yieldably resisting the action of said speed governor, pressure responsive means for varying the resistance offered by said yieldable means, means for subjecting said last mentioned means continuously to compressor discharge pressure, a second throttle valve for controlling the supply of operating fluid to the engine, pressure responsive means operative on the supply of operating fluid thereto to move said second throttle valve to a position effecting operation of the engine at an idling speed, and means controlled by said first mentioned pressure responsive means for supplying pressure fluid to and venting pressure fluid from said second mentioned pressure responsive means and said unloading means, said means for supplying pressure fluid to and venting pressure fluid from said second mentioned pressure responsive means and said unloading means including a vent controlling valve and a pressure fluid supply valve movable by said vent controlling valve, said pressure responsive means including a lever pivotable to vary the resistance offered by said yieldable means and when substantially in one limiting position thereof engageable with said vent controlling valve to actuate the latter.

22. A regulating mechanism for an engine driven compressor having fluid actuated unloading means and fuel regulating means for the engine, comprising, in combination, a control member, means operatively connecting said control member to the fuel regulating means for the engine, a pressure responsive device connected to said control member and operative by pressure fluid supplied thereto for actuating said control member to effect a reduction in fuel supply to the engine, means for continuously supplying fluid discharged by the compressor to said pressure responsive device, and valve means controlled by said pressure responsive device for controlling the flow of fluid relative to said fluid actuated compressor unloading means to effect compressor unloading and loading.

23. A regulating mechanism for an engine driven compressor having fluid actuated unloading means and fuel regulating means for the engine, comprising, in combination, a control member, means operatively connecting said control member to the fuel regulating means for the engine, a pressure responsive device connected to said control member and operative by pressure fluid supplied thereto for actuating said control member to effect a reduction in fuel supply to the engine, means for continuously supplying fluid discharged by the compressor to said pressure responsive device, and means including a valve member movable by said pressure responsive device to a position permitting fluid to flow

to the unloading means and operating in such position to prevent further movement of said control member by said pressure responsive device.

24. A regulating mechanism for an engine driven compressor having fluid actuated unloading means and fuel regulating means for the engine, comprising, in combination, a control member, means operatively connecting said control member to the fuel regulating means for the engine, a pressure responsive device operatively connected to said control member and operative by pressure fluid supplied thereto for actuating said control member to effect a reduction in fuel supply to the engine, means for supplying fluid discharged by the compressor to said pressure responsive device, unloading means controlling means including a valve member movable by said pressure responsive device to a position permitting fluid discharged by the compressor to flow to the unloading means, means for subjecting said valve member to a pressure in a direction opposing its movement by said pressure responsive device, and means for causing said valve member to be subjected to a lesser net pressure in such direction after movement by said pressure responsive device.

25. A regulating mechanism for an engine driven compressor having fluid actuated unloading means and fuel regulating means for the engine, comprising, in combination, a control member, means operatively connecting said control member to the fuel regulating means for the engine, a pressure responsive device operatively connected to said control member and operative by pressure fluid supplied thereto for actuating said control member to effect a reduction in fuel supply to the engine, means for supplying fluid discharged by the compressor to said pressure responsive device, pressure responsive means operative on the supply of pressure fluid thereto for effecting a slowing down of the engine to an idling speed, means for effecting compressor unloading and a further slowing down of the engine including a valve member movable by said pressure responsive device to a position for supplying fluid discharged by the compressor to the unloading means and to said pressure responsive means, means for subjecting said valve member to a pressure in a direction opposing its movement by said pressure responsive device, and means for causing said valve member to be subjected to a lesser net pressure in said direction after movement by said pressure responsive device.

26. A regulating mechanism for an engine driven compressor having fluid actuated unloading means and fuel regulating means for the

engine, comprising, in combination, a control member, means operatively connecting said control member to a fuel regulating means for the engine, a pressure responsive device operatively connected to said control member and operative by pressure fluid supplied thereto for actuating said control member to effect a reduction in fuel supply to the engine, means for supplying fluid discharged by the compressor to said pressure responsive device, means for conducting fluid to and from the compressor unloading means, and a pair of valve members for controlling the connection of said fluid conducting means to atmosphere and to the compressor discharge, one of said valve members movable by said pressure responsive device and operating to position the other of said valve members.

27. A regulating mechanism for an engine driven compressor having fluid actuated unloading means and fuel regulating means for the engine, comprising, in combination, a control member, means operatively connecting said control member to a fuel regulating means for the engine, a pressure responsive device operatively connected to said control member and operative by pressure fluid supplied thereto for actuating said control member to effect a reduction in fuel supply to the engine, means for supplying fluid discharged by the compressor to said pressure responsive device, means for conducting fluid to and from the compressor unloading means, and a pair of valve members for controlling the connection of said fluid conducting means to atmosphere and to the compressor discharge, one of said valve members movable by said pressure responsive device and operating to position the other of said valve members, means for subjecting said valve members to pressures in a direction opposing their movement by said pressure responsive device and means for reducing the net cumulative pressure acting on said valve members in said direction after movement thereof by said pressure responsive device.
